HEMOGLOBINOMETER

Albin A. Gradišar, Buffalo, and Morden G. Brown, Williamsville, N. Y., assignors, by mesne assignments, to American Optical Company, Southbridge, Mass., a voluntary association

Application April 25, 1942, Serial No. 440,476

7 Claims.

(Cl. 88—14)

This invention relates to hemoglobinometers and more particularly to an instrument which is compact and portable and easily carried by the physician for use on his calls for making routine examination of the hemoglobin content of the blood.

An object of the invention is to provide a hemoglobinometer which is compact and portable and which may be used by the physician on his calls for making routine blood examinations and wherein the blood examinations can be easily and quickly made with only a drop of blood and without any chemical preparation of the sample.

Another object of the invention is to provide a new and improved sighting arrangement for hemoglobinometers of the type set forth.

Another object of the invention is to provide a device of the type set forth having new and improved optical means which provides adjacent fields for matching and also allows making the instrument of convenient size and shape.

Other objects and advantages of the invention will be apparent from the following description taken in connection with the accompanying drawings. It will be apparent that many changes may be made in the details of construction and arrangement of parts without departing from the spirit of the invention as expressed in the accompanying claims. We therefore do not wish to be limited to the exact details of construction and arrangement of parts shown, and described as the preferred form has been shown by way of illustration only.

Referring to the drawings:

Fig. 1 is a side view of the instrument.

Fig. 2 is a top plan view thereof.

Fig. 3 is a view of the opposite side thereof.

Fig. 4 is a sectional view taken on line 4—4 of Fig. 2 looking in the direction of the arrows.

Fig. 5 is a sectional view taken on line 5—5 of Fig. 4 looking in the direction of the arrows.

Fig. 6 is a sectional view taken on line 6—6 of Fig. 4 looking in the direction of the arrows.

Fig. 7 is a sectional view taken on line 7—7 of Fig. 4 looking in the direction of the arrows.

Fig. 8 is a sectional view taken on line 8—8 of Fig. 4 looking in the direction of the arrows.

Fig. 9 is a sectional view taken on line 9—9 of Fig. 4 looking in the direction of the arrows.

Fig. 10 is a perspective view of the specimen chamber; and

Fig. 11 is a perspective view of the prism member.

Referring more particularly to the drawings

wherein similar reference characters designate corresponding parts throughout the several views, the instrument as shown, comprises a casing formed of two separate sections 1 and 2, having interfitting abutting edges 3 and 4, and adapted to be retained in assembled relation by the spring clips or the like 5 which are secured to the section 2 adjacent the ends of said section 2 and are adapted to resiliently engage depressions or openings in the other of said sections as is shown in Fig. 4.

The casing sections 1 and 2 are preferably molded of plastic or similar material such as Bakelite or the like but may be formed from any other desired material.

The lower casing section 2 is adapted to contain the dry cell batteries 6 and 7 and the lamp or bulb 8 and reflector 9.

The lamp 8 is preferably of the usual type employed in flashlights and the reflector 9 is adapted to surround said lamp 8 and reflect light through the standard and specimen as herein-after described.

The battery contact member 10 for the battery 7 has the resilient portion 11 adapted to resiliently engage the contact on the battery and has its opposite end 12 secured to the switch member 13 which may be pressed with the finger to cause said end 12 to engage the center contact 14 of the lamp to cause the lamp 8 to be lighted, and the member 14 for the other battery 6 has the resilient portion 15 engaging the contact on the battery and its opposite end 16 secured to the contact 17 which resiliently engages the bottom of the battery 6. The contact member 18 is secured at one end to the lamp socket 18 and at its other end resiliently engages the bottom of the battery 6.

In the upper section 1 of the casing is the partition 19 on which is slideably positioned the standard or wedge 20 in the slideway 21. This standard member 20 comprises an absorption wedge supported by the frame member 22 having the button portion 23 adapted to slide in a slot in the wall of the section 1 whereby movement of said button member 23 will cause longitudinal movement of the frame 22 and color wedge 20.

To support the blood specimen we have provided the resilient supporting member 25 which is adapted to receive and support the member 26 which is formed of glass or other transparent material and which has the slot or groove 27 in the upper face thereof over which the cover plate 28 is adapted to be retained by the resilient fingers 29 of said support 25. This specimen

holder is generally similar to the usual haemacytometer except for size and measuring indications.

The support member 25 is provided with the finger members 30 which project outwardly and when the support is placed in the instrument allow the gripping of said fingers 30 for insertion in or removal from the opening 31 in the instrument.

Over the light source or lamp 8 and beneath the color wedge 20 and the member 26 is provided the support 32 adapted to contain the combination color filter and diffusing unit 33. The opening 31 for insertion of the sample or specimen holder 25 is so positioned in the upper section 1 of the casing that the standard or absorption wedge and sample are in substantially the same plane so that when the wedge is compared with the specimen the two fields will be practically identical in appearance.

The partition 19 and the guideway or slide-way 21 are provided with the openings 34 and 35 in alignment with the lamp 8, color filters 33 and adjacent portions of the wedge 20 and specimen support 25 so that said adjacent portions of the absorption wedge and the specimen in the specimen chamber 26 will be illuminated from below by the lamp 8 and the rays brought into adjacent areas by the prism 36 and the said adjacent portions of said wedge 20 and specimen may then be seen side by side for comparison through the lens 37 and sight tube 38.

As shown in Fig. 1 on the side of the instrument adjacent the button or the like 23 for adjusting the wedge 20, and which button has the index mark 39 thereon, are provided the scales 40 and 41. These scales are adapted to be read to give the measurement of the hemoglobin content of the blood sample in the instrument.

The wedge 20 is a standard or thickness gradient of homogeneous absorption material and may be formed of a gelatin substance containing light absorbing material. The said wedge 20 is adapted to change the light intensity until the light intensity is the same in the two adjacent fields and by adjusting said wedge a match point is reached depending on the hemoglobin content of the blood sample.

The prism member 36, as shown in Fig. 11, is a combination biprism and reflecting prism, that is, it bends or reflects the light rays and allows the making of the instrument of a convenient size and shape and also performs the functions of a biprism in that it brings the adjoining positions of the sample and standard into adjacent relation for matching. This prism functions both as a reflecting prism and as a biprism because of its shape as shown in Fig. 11. The prism 36 comprises the flat or plane hypotenuse 47 and the wedge shaped entrance surface 48 and inverted wedge shaped exit surface 49. Because of the wedge shaped entrance and exit surfaces the separate fields are made adjacent without a gap or a disturbing dividing line.

It will be noted, as shown in Fig. 4, that a diaphragm is placed over the face of the prism toward the sight opening and said diaphragm divides the field into three parts with dark lines between said parts of the field. This will divide the field into three different parts, that is, because of the difference in thickness of the areas of the color standard one side of the field will be darker than the center area and the other side of the field will be lighter than the center area.

This will facilitate the setting of the instrument and matching of the fields. This diaphragm consists of the members 44 and 46 in the upper and lower edges of the field respectively and the members 42 and 43 divide the field into three parts. The members 42 and 43 may be merely wire or the like so positioned as to extend across the field to divide the same into three areas or parts.

In the use of the instrument the doctor introduces a drop of blood in the blood chamber 26. The blood may be introduced by capillarity after the members 26 and 28 have been placed in the resilient sample container 25 or by pipette or other means prior to assembly of this chamber. This assembled chamber is then placed in the opening 31 in the upper section 1 of the instrument. The button 13 is then depressed to cause current from the batteries 6 and 7 to illuminate the lamp or bulb 8 and then while viewing through the lens 37 and sight tube 38 the wedge 20 is moved or adjusted by means of the button 23 until the adjacent fields of the wedge 20 and blood sample appear substantially identical and then the measurement of the hemoglobin content is read from the scales 40 or 41.

The instrument described above provides a compact and easily portable device for measuring the hemoglobin content of the blood and which device may be easily carried by the doctor on his calls to facilitate routine blood examinations which may be made at that time. With this construction it is not necessary to have any chemical preparation of the blood sample and as only a drop of blood is necessary for the test it can be drawn directly into the sample holder. It is further pointed out that due to the simplification of the apparatus and the technique employed, no extended training is required for the use of the device.

From the foregoing it will be seen that we have provided simple, efficient and economical means of obtaining all of the objects and advantages of the invention.

Having described our invention, we claim:

1. In a device of the character described, an elongate casing, a standard member mounted for adjusting movement within said elongate casing, a light source in said casing for projecting light transversely thereof through the portion of said standard member brought into alignment with the source, a specimen holder mounted in adjacent relation with the portion of said standard member which is in alignment with said light source, said specimen holder being adapted to contain a specimen to be compared with said standard member, and said standard member and said specimen holder being positioned so that they are substantially equally illuminated by the light projected from said light source, reflector means closely adjacent to and overlying said standard member and specimen holder and aligned with viewing means extending longitudinally of said casing and cooperating with said reflector means to permit simultaneous observation of the adjacent portions of the standard member and of a specimen in said specimen holder, said viewing means comprising a sight tube housed within said elongate casing and aligned with an opening at one end of the casing, said tube being formed on at least one side by a wall of said casing.

2. In a device of the character described, an elongate casing, a light source within the casing for projecting light transversely thereof, a diffus-

ing plate illuminated by said light source, reflector means in said casing overlying said diffusing plate, a standard member and a specimen holder mounted in adjacent relation between said reflector means and said diffusing plate, said standard member being mounted for adjusting movement so as to bring a selected portion of said standard member into alignment with said diffusing plate, and viewing means extending longitudinally of said casing and aligned with said reflector means to permit simultaneous observation of the adjacent portions of the standard member and of a specimen in said specimen holder, said viewing means comprising a sight tube housed within said elongate casing and aligned with an opening at one end of the casing, said tube being formed on at least one side by a wall of said casing.

3. In a device of the character described, a casing, a standard member and a specimen holder mounted within said casing in adjacent relation, said standard member being adjustably mounted to bring a selected portion of said standard member into adjacent relation with said specimen holder, reflector means overlying said standard member and specimen holder and aligned with viewing means housed within said casing and opening through a wall thereof for presenting images of areas of the standard member and specimen for comparison, said reflector means comprising a bi-prism for bringing said images into touching relation, and said bi-prism having a pair of entrance surfaces one overlying the specimen and the other overlying the standard, a reflector surface in reflecting relation to said entrance surfaces and a pair of exit surfaces forming a re-entrant angle to bring the reflected images of said areas into touching relation.

4. In a device of the character described, an elongate casing comprising a pair of separable sections, means for retaining said sections in assembled relation, one of said sections containing a light source for projecting light into the other section, a partition having a window forming a chamber in the last mentioned section adapted to receive light only through said window, said window being aligned with said source, means in said casing for removably supporting a specimen holder to overlie a portion of said window, a standard member adjustably mounted for movement over said window to bring a selected portion of said member into registry therewith and in adjacent relation with said specimen holder, reflector means mounted in said casing spaced from said window and overlying said specimen holder and the adjacent portion of said standard member, and a sight tube housed within said

- casing extending longitudinally thereof and aligned with said reflector means for viewing in adjacent relation the specimen holder and the selected portion of said standard member as illuminated by said light source, at least one side of said sight tube being formed by a wall of said casing, said tube being aligned with an opening at one end of the casing.
5. In a device of the character described, an elongated casing, a source of illumination in said casing, a longitudinal partition in said casing having a window aligned with said source for transmitting light therefrom, an eyepiece mounted in an opening in the casing wall adjacent one end of the casing, reflector means housed within the casing in spaced relation with said window and optically aligned therewith and with said eyepiece, means in said casing for removably supporting a specimen holder to overlie a portion of said window beneath said reflector means, and a standard member adjacent said specimen holder and adjustably mounted for bringing a selected portion of said member into registry with said window beneath said reflector means, said casing being divided longitudinally into sections, one of said sections carrying said source and being separable from the other section, and means for retaining said sections in assembled relation.
- 10 6. In a device of the character described, a casing containing a source of illumination, an eyepiece mounted in an opening in the casing wall, reflector means in said casing optically aligned with said source of illumination and with said eyepiece, a standard member and a sample holder mounted in adjacent relation between said reflector means and said source of illumination, and means for adjusting said standard member to bring a selected portion thereof into aligned relation with said reflector means and said source of illumination, said reflector means comprising a bi-prism cooperating with said eyepiece for presenting images of areas of said standard member and sample holder in touching relation for ready comparison, and said bi-prism having entrance surfaces for receiving light from adjacent areas of said standard member and sample, a reflector surface in reflecting relation to said entrance surfaces and a pair of exit surfaces forming a re-entrant angle to bring the reflected images of said areas into touching relation.
- 15 7. In a device of the character described, the combination as set forth in claim 6 in which the entrance surfaces of said prism form an external angle.
- 20 8. In a device of the character described, an elongated casing, a source of illumination in said casing, a longitudinal partition in said casing having a window aligned with said source for transmitting light therefrom, an eyepiece mounted in an opening in the casing wall adjacent one end of the casing, reflector means housed within the casing in spaced relation with said window and optically aligned therewith and with said eyepiece, means in said casing for removably supporting a specimen holder to overlie a portion of said window beneath said reflector means, and a standard member adjacent said specimen holder and adjustably mounted for bringing a selected portion of said member into registry with said window beneath said reflector means, said casing being divided longitudinally into sections, one of said sections carrying said source and being separable from the other section, and means for retaining said sections in assembled relation.
- 25 9. In a device of the character described, an elongated casing, a source of illumination in said casing, a longitudinal partition in said casing having a window aligned with said source for transmitting light therefrom, an eyepiece mounted in an opening in the casing wall adjacent one end of the casing, reflector means housed within the casing in spaced relation with said window and optically aligned therewith and with said eyepiece, means in said casing for removably supporting a specimen holder to overlie a portion of said window beneath said reflector means, and a standard member adjacent said specimen holder and adjustably mounted for bringing a selected portion of said member into registry with said window beneath said reflector means, said casing being divided longitudinally into sections, one of said sections carrying said source and being separable from the other section, and means for retaining said sections in assembled relation.
- 30 10. In a device of the character described, an elongated casing, a source of illumination in said casing, a longitudinal partition in said casing having a window aligned with said source for transmitting light therefrom, an eyepiece mounted in an opening in the casing wall adjacent one end of the casing, reflector means housed within the casing in spaced relation with said window and optically aligned therewith and with said eyepiece, means in said casing for removably supporting a specimen holder to overlie a portion of said window beneath said reflector means, and a standard member adjacent said specimen holder and adjustably mounted for bringing a selected portion of said member into registry with said window beneath said reflector means, said casing being divided longitudinally into sections, one of said sections carrying said source and being separable from the other section, and means for retaining said sections in assembled relation.
- 35 11. In a device of the character described, an elongated casing, a source of illumination in said casing, a longitudinal partition in said casing having a window aligned with said source for transmitting light therefrom, an eyepiece mounted in an opening in the casing wall adjacent one end of the casing, reflector means housed within the casing in spaced relation with said window and optically aligned therewith and with said eyepiece, means in said casing for removably supporting a specimen holder to overlie a portion of said window beneath said reflector means, and a standard member adjacent said specimen holder and adjustably mounted for bringing a selected portion of said member into registry with said window beneath said reflector means, said casing being divided longitudinally into sections, one of said sections carrying said source and being separable from the other section, and means for retaining said sections in assembled relation.
- 40 12. In a device of the character described, an elongated casing, a source of illumination in said casing, a longitudinal partition in said casing having a window aligned with said source for transmitting light therefrom, an eyepiece mounted in an opening in the casing wall adjacent one end of the casing, reflector means housed within the casing in spaced relation with said window and optically aligned therewith and with said eyepiece, means in said casing for removably supporting a specimen holder to overlie a portion of said window beneath said reflector means, and a standard member adjacent said specimen holder and adjustably mounted for bringing a selected portion of said member into registry with said window beneath said reflector means, said casing being divided longitudinally into sections, one of said sections carrying said source and being separable from the other section, and means for retaining said sections in assembled relation.
- 45 13. In a device of the character described, an elongated casing, a source of illumination in said casing, a longitudinal partition in said casing having a window aligned with said source for transmitting light therefrom, an eyepiece mounted in an opening in the casing wall adjacent one end of the casing, reflector means housed within the casing in spaced relation with said window and optically aligned therewith and with said eyepiece, means in said casing for removably supporting a specimen holder to overlie a portion of said window beneath said reflector means, and a standard member adjacent said specimen holder and adjustably mounted for bringing a selected portion of said member into registry with said window beneath said reflector means, said casing being divided longitudinally into sections, one of said sections carrying said source and being separable from the other section, and means for retaining said sections in assembled relation.
- 50 14. In a device of the character described, an elongated casing, a source of illumination in said casing, a longitudinal partition in said casing having a window aligned with said source for transmitting light therefrom, an eyepiece mounted in an opening in the casing wall adjacent one end of the casing, reflector means housed within the casing in spaced relation with said window and optically aligned therewith and with said eyepiece, means in said casing for removably supporting a specimen holder to overlie a portion of said window beneath said reflector means, and a standard member adjacent said specimen holder and adjustably mounted for bringing a selected portion of said member into registry with said window beneath said reflector means, said casing being divided longitudinally into sections, one of said sections carrying said source and being separable from the other section, and means for retaining said sections in assembled relation.
- 55 15. In a device of the character described, an elongated casing, a source of illumination in said casing, a longitudinal partition in said casing having a window aligned with said source for transmitting light therefrom, an eyepiece mounted in an opening in the casing wall adjacent one end of the casing, reflector means housed within the casing in spaced relation with said window and optically aligned therewith and with said eyepiece, means in said casing for removably supporting a specimen holder to overlie a portion of said window beneath said reflector means, and a standard member adjacent said specimen holder and adjustably mounted for bringing a selected portion of said member into registry with said window beneath said reflector means, said casing being divided longitudinally into sections, one of said sections carrying said source and being separable from the other section, and means for retaining said sections in assembled relation.
